UNITED STATES PATENT OFFICE.

GUSTAV SCHÜNEMANN AND OTTO RIEDER, OF BUDA-PESTH, AUSTRIA-HUNGARY.

ELECTRIC GAS-LIGHTING DEVICE.

SPECIFICATION forming part of Letters Patent No. 647,617, dated April 17, 1900.

Application filed April 29, 1899. Serial No. 714,964. (No model.)

To all whom it may concern:

Be it known that we, GUSTAV SCHÜNEMANN and OTTO RIEDER, subjects of the Emperor of Austria-Hungary, residing at Buda-Pesth, in the Empire of Austria-Hungary, have invented certain new and useful Improvements in Electric Gas-Lighting Devices, (for which we have applied for patents in England, dated March 8, 1899, No. 5,111; in Germany, dated 10 January 14, 1899, and February 25, 1899; in Hungary, dated January 31, 1899, No. 1,454; in France, dated January 21, 1899, No. 273,086, and March 4, 1899, No. 274,404; in Belgium, dated March 4, 1899, No. 110,782, and in Italy, 15 dated March 7, 1899,) of which the following is a specification.

This invention relates to electric gas-lighting devices, and embraces means for operating the supply-cock electrically and electrical 20 means for igniting the gas.

It is an object of this invention to enable the gas to be turned on and simultaneously ignited at a distance by electrical devices.

In the drawings, Figure 1 is a side elevation of electrical gas-cock-operating devices embodying our invention with the inclosing case in vertical section. Fig. 2 is a plan view of the same with the top of the case removed, and Fig. 3 is a diagrammatic plan view of the 30 electrical igniting devices.

In Figs. 1 and 2 the gas-cock or supply-valve is illustrated as being actuated by an electric current acting on the electromagnet *f*, which current is thrown on or off by a switch 35 or key. The armature *g* is drawn to the magnet and is provided at its free end with a lever *e*, the hinged head or pawl *e'* of which is capable of being tilted up. When the armature is drawn up, the hinged head *e'* engages 40 with a tooth of the ratchet-wheel *d* and turns it the space of one tooth. The ratchet-wheel *d* is provided with holes *c*², arranged in a circle, there being half as many holes as there are teeth on the disk. The ratchet-wheel *d* 45 is pressed up air-tight by means of the spring *h* against the surface of the gas-pipe, which is provided with corresponding escape-openings *c'*, and when the whole of the holes coincide the gas will pass through them into the air-tight casing *m*, which surrounds the whole of 50 the mechanism, then through the cross-open-

ing *b*, and through the pipe *a* to the burner, where it is ignited. The hinged head or pawl *e'* of the lever or pawl *e* is retained in its normal position by the action of the small spring *i*, and is thus enabled to pass the projecting tooth of the disk *d* without turning it back, and the armature *g* will be free to fall back into its original position. The teeth of the ratchet-wheel *d* and the stroke or traverse of 55 the lever or pawl *e* are so arranged that the holes *c*² only coincide with the holes *c'* after every second lift of the lever and pawl *e e'*. If now the current is again shut off, the ratchet-wheel *d* will only have been moved 60 so far that the escape-openings *c'* are covered, the cock closed, and the further supply of gas shut off. In order that the ratchet-wheel *d* after being lifted or moved by the lever and pawl *e e'* should not turn farther than 70 necessary, an arm *k* is attached to the armature *g*, which when the lever and pawl *e e'* have reached their highest position comes in contact with the pins *l* and prevents the ratchet-wheel *d* from turning farther.

The middle apparatus A of Fig. 3 represents the central vibrator and consists of the electromagnet *M*² in connection with the source *B*² of electric current and the switch or key *E*, while the apparatus B and C shown 75 to the left and right of A represent the local vibrators, and these also consist of electromagnets *M'* and *M*³, furnished with batteries *B'* and *B*³, each having an induction-coil *I'* and *I*³ placed in the circuit of the battery-current. These local vibrators are placed at the 80 point where the ignition takes place, and the requisite number of them are inserted in the lines or conducting-wires *v* *v*² of the central vibrator. The magnet *f*, which controls the 85 gas-cock or supply-valve, is in circuit with the battery *B*². The coils of the electromagnet *M*² are connected with the wires of the battery *B*², the circuit of which is closed when the switch *E* is closed, and at the same time 90 the armature *A*² of the electromagnet is drawn back. The armature is shown in this position in the drawing. In this case the current takes the following course: from one pole of the battery *B*² through the switch *E*, clamping-screw *K*², armature *A*², and set-screw *S*² 95 to the coils of the electromagnet *M*², and from

there through the clamping-screw K⁴ and the conducting-wire v' to the other pole of the battery B². On closing the switch E by moving an ordinary knob or handle, for example, 5 the current of the battery B² will circulate in the electromagnet M², causing the latter to immediately attract the armature A², and in so doing the circuit will be broken at the screw S⁵. The electromagnet then liberates 10 the armature A², and the circuit is again closed. This action is repeated continuously, and thereby the armature A² is caused to vibrate violently. The vibrating armature A² serves to close or complete and interrupt or 15 break the circuit of the current circulating through the electromagnets M' M³ of the vibrators B C by coming into contact as often as it is attracted by the electromagnet by means of a spring with the set-screw S⁴, and 20 thereby closing or completing the following circuits: first, from one pole of the battery B² through the switch E, clamping-screw K⁵, armature A², set-screw S⁴, clamping-screw K⁶, conducting-wire v², and clamping-screw K' to 25 the coils of the electromagnet M', and from there through the clamping-screw K² and conducting-wire v' back to the other pole of the battery B²; second, from one pole of the battery B² through the switch E, clamping-screw 30 K⁵, armature A², set-screw S⁴, clamping-screw K⁵, and clamping-screw K⁷ to the electromagnet M³, and from there through the clamping-screw K⁸ and conducting-wire v' back to the other pole of the battery B². In a similar 35 manner any desired number of vibrators B C can be connected with the lines or conducting-wires v' v² of the central vibrator A.

The mode of action of the apparatus is as follows: By closing the switch E the circuit 40 of the battery B² is closed with the central vibrator A. The electromagnet M² is thus caused to attract the armature A². At the moment this takes place the contact of the armature is withdrawn from the set-screw S⁵, 45 and simultaneously the armature through its upper contact is caused to touch the set-screw S⁴, so that from this time the current leaving the coils of the electromagnet M² runs through the clamping-screw K⁵ and armature A² to 50 the set-screw S⁴, from there through the clamping-screw K⁶ and wire v² into the vibrators B C by the clamping-screws K' and K⁷, and from there through the coils of the electromagnets M' and M³, set-screws K² and K⁸, and 55 conducting-wire v' back to the battery B² of the central vibrator A. As, however, in this position, as before mentioned, the current does not run through the coils of the electromagnet M², the armature A² is not attracted. 60 The current which the electromagnets M' and M³ thus receive consists, therefore, of a momentary impulse. The action repeats itself automatically by closing or completing the circuit of the battery B², and the vibration 65 of the armature A² in the central vibrator corresponds to the vibration of the armatures A' and A² in the vibrators B and C.

When the electromagnets M' and M³ set the armatures A' and A³ in vibration, they effect the closing or completion and the interruption or breaking of the circuit of the batteries B' and B³, by which means a current is induced in the secondary induction-coils I' and I² which possesses a force or intensity suitable for the production of an electric spark 70 between the points at F' and F² for the purpose of lighting a gas-burner. When the vibration of the armatures A' and A³ is caused by the armature A² of the central vibrator A, the lower contacts of the armatures A' and A³ are made to touch the set-screws S² and S⁷, 75 whereby the current from B' and B³ has a free course through the clamping-screws K³ and K⁹, as well as through the set-screws S² and S⁷, armatures A' and A³, clamping-screws 80 K² and K⁸, and through the induction-coils I' and I² and back to the batteries B' and B³. The closing and interrupting of this circuit caused by the vibration of the armatures A' and A³ produce, by means of the induction-coils I' and I², a violent formation of sparks 85 at F' and F². 90

In order to make the formation of sparks still more active, condensers C' and C² may be introduced between the armature A' and the set-screw S² and between the armature A³ and the set-screw S⁷. 95

The screws S³, S', and S⁶ are used for setting the armatures A², A', and A³ and for regulating the contacts. 100

By disconnecting the switch E the electric current may be shut off from the whole arrangement.

What we claim, and desire to secure by Letters Patent of the United States, is— 105

1. In electric gas-lighting devices, the combination of a gas-burner, a main source of electrical energy, a main vibrator in circuit therewith, a local interrupting-vibrator, spark-gap terminals adjacent to the burner, electrical circuits for energizing the local interrupting-vibrator controlled by the main vibrator, and means for producing high-tension currents electrically connected between the spark-gap terminals and the local interrupting-vibrator. 110 115

2. In electric gas-lighting devices, the combination of a gas-burner, a main source of electrical energy, a main vibrator in circuit therewith, a local interrupting-vibrator, spark-gap terminals adjacent to the burner, electrical circuits for energizing the local interrupting-vibrator controlled by the main vibrator, means for producing high-tension currents electrically connected between the spark-gap terminals and the local interrupting-vibrator, 120 and an electrically-controlled supply-valve for supplying gas to the burner connected with the main source of electrical energy. 125

3. In electric gas-lighting devices, the combination of a gas-burner, a main source of electrical energy, a main vibrator in circuit therewith, a local interrupting-vibrator, spark-gap terminals adjacent to the burner, electrical circuits for energizing the local interrupting- 130

vibrator controlled by the main vibrator, an induction-coil in circuit with said local interrupting-vibrator, a local source of electrical energy in circuit with said induction-coil, and § an electrical circuit between said induction-coil and the spark-gap terminals.

4. In electrical gas-lighting devices, the electrically-operated apparatus for controlling the gas-supply, consisting of a closed chamber having a gas-outlet, a gas-pipe entering said chamber, and provided with a series of supply-outlets c' , the ratchet-disk d , provided with a series

of openings c^2 adapted to register with the outlets c' , the spring h , and the electrically-operated pawl for operating the ratchet-disk, 15 combined and operating substantially as and for the purposes described.

In testimony whereof we have hereunto set our hands in the presence of two witnesses.

GUSTAV SCHÜNEMANN.

OTTO RIEDER.
